This 26th

UNITED STATES PATENT OFFICE.

HANS H. HANSEN, OF CHICAGO, ILLINOIS.

ELECTRIC SNAP-SWITCH.

1,126,455.

Specification of Letters Patent. Patented Jan. 26, 1915.

Application filed January 11, 1912. Serial No. 670,620.

To all whom it may concern:

Be it known that I, HANS H. HANSEN, a citizen of the United States, residing at Chicago, in the county of Cook and State of Illinois, have invented certain new and useful Improvements in Electric Snap-Switches, of which the following is a specification.

My invention relates to electric snap switches and the object thereof is to provide a switch of this character which is simple and economical of manufacture and efficient and reliable in operation.

The features of advantage and utility in my construction of switch will be apparent from the description hereinafter given.

In the accompanying drawing, Figure 1 is an elevation of the switch with the case and turn button removed; Fig. 2 a central section on the line 2—2 of Fig. 1; Fig. 3 an elevation of the switch complete but shown on a smaller scale than Figs. 1 and 2; Fig. 4 an elevation of the indicating dial; Fig. 5 a detail view of the ratchet and operating parts immediately associated therewith; Fig. 6 an elevation of the switch plate and frame carrying the same together with other operating parts associated therewith; Fig. 7 a perspective of the switch plate, frame and spindle; Fig. 8 an elevation of a washer or plate secured to the spindle and co-operating with the spring and Fig. 9 a perspective of the washer or plate secured to the spindle and interlocked with the indicating dial.

The present embodiment of my invention is illustrated in the drawings in which the switch is shown as composed of the base portion or block 1 of suitable non-conducting material such as porcelain, a case 2 mounted thereon, and switch mechanism contained therewithin. Within the case and upon one side of the block are two similar contacts 3 arranged diametrically opposite each other and provided with upturned flanges 3^a forming binding posts in connection with the screws 4. By preference and as herein shown these contact plates are secured to the base block by means of the screws 5 and also by the lugs 6^a entering openings 1^a in such base block.

A stationary ratchet 6 having a suitable number of teeth 6^a, here four in number, Figs. 1 and 5, is secured in suitable manner to the inner side of the base block and centrally thereof, the same being in the

present instance held against rotation by means of its lugs 6^a which enter corresponding holes 1^a in the base block, Fig. 2.

A spindle 7 passes centrally through the base block and ratchet 6 and also through the case, its outer exposed end being screw-threaded to receive the usual turn button 8. This spindle passes through a bushing 9 in the block and is held in place by means of the washer 10 at its outer end.

Upon the spindle at a point beyond the ratchet 6 is secured an eccentric or cam 11 which operates within a cam opening 12^a of a cam plate 12 which is provided with a lug 12^b adapted to co-operate with the teeth 6^a of the ratchet in the manner hereinafter explained. This cam plate is provided with a laterally extending pin 13 which enters a corresponding opening of a frame 14 which comprises a bottom portion 14^a, two similar and parallel arms 14^b extending at right angles to the bottom portion, and a connecting plate or piece 14^c which has near its ends openings adapted to receive the free ends of said arms. This cross piece 14^c is also provided with a central opening to accommodate the spindle 7. By reason of this construction of frame the arms referred to are securely held as to their outer ends and at the same time provision is made for the ready detachment of the parts inasmuch as the cross piece 14^c is merely interlocked with said arms. This cross piece is held in proper operative relationship with the arms by means of the washer 15 which is removably secured to the spindle.

The frame 14 carries the switch plate 16 whose pairs of contacts 16^a at its ends are adapted to co-operate with the contacts 3 in alternate positions of the frame and spindle, said switch plate and contacts being of the knife type. The switch plate is threaded upon the arms 14^b of the frame 14 and held in proper position intermediate the length of these arms in suitable manner preferably by means of the pairs of plates 17 between which and the switch plate are interposed strips 18 of insulating material. The innermost plates 17 rest against shoulders 14^c on the arms 14^b and the outermost of these plates are held in position by slightly expanding the shoulders 14^c by some suitable tool so that such plates are securely held upon said arms.

A coiled spring 19 surrounds the spindle

7 intermediate its length with one end secured to the frame 14 and the other bearing against a lug 20^a of a washer 20 applied to and clamped upon the spindle, Figs. 2, 5 6 and 8. As shown in detail in Fig. 8 this washer or plate is of a type having a radial slot 20^b which fits upon the spindle with the result that when the washer is clamped together it is held firmly to the spindle.

10 At a point beyond the frame 14 there is secured to the spindle a washer or plate 21 shown in detail in Fig. 9 and preferably of the same general character as to attachment to the spindle as the washer 20 above described. This washer 21 is provided with a pair of outwardly extending lugs 21^a which are adapted to interlock with the usual indicating dial 22 having the usual indications "off" and "on" for indicating whether the 15 current is off or on, that is, whether the circuit is open or closed. This dial is provided with diametrically opposite openings 22^a adapted to receive the lugs 21^a of the washer 21 with the result that the dial is interlocked with such washer. When the 20 case 2 is in place the dial is held in place upon the washer but when removed, such dial can be readily detached thereby giving convenient access to the switch mechanism 25 proper without liability of injuring the dial, which would otherwise result if such dial were held permanently fixed in place. It will be understood that the case is provided with a slot 2^a adapted to expose the 30 indications on the dial.

The operation of the switch will be apparent from the description hereinbefore given. When the switch plate is in the position indicated in Fig. 1, the current is on 35 as such plate connects the two contacts 3. When, however, the button is turned in a clockwise direction the spindle 7 will be correspondingly rotated thereby increasing the tension of the coiled spring. At the same 40 time the cam 11 will, by progressive movement, release the cam plate from engagement with the ratchet with the result that

such plate, frame 14 and switch plate will be rotated a quarter turn by the tension of the spring until the lug 12^b is arrested by 50 the next tooth of the ratchet. At this time the switch plate is out of contact with the contacts 3 and the current is therefore off. Continued movement of the button will operate the cam plate, frame and switch plate 55 as before, so as to bring the latter to a position of contact with both the said contacts.

The switch as constructed by me is comparatively simple and economical of manufacture and is moreover capable of being 60 very readily assembled or taken apart.

Furthermore, the provision of the cross piece 14^a provides a rigid construction of frame and at the same time enables the convenient assembling of the switch plate 65 thereon.

Furthermore, the interlocking connection between the indicating dial and its washer 21 enables such dial to be readily removed to prevent injury whenever the switch is 70 being repaired or wires are being attached to the binding posts.

I claim:

1. In an electric switch, the combination, with the contacts and switch plate and with 75 the spindle coöperating therewith, of an indicating dial, and a plate which is secured to the spindle and with which the dial has interlocking connection, said latter plate having a radial slot whereby it is interlocked with the spindle.

2. In an electric switch, the combination, with the contacts and switch plate and with the spindle coöperating therewith, of an indicating dial, and a plate having a radial 85 slot for securing it to the spindle and having projecting lugs, said dial having holes corresponding to said lugs for interlocking connection of the dial and plate.

HANS H. HANSEN.
